UNITED STATES PATENT OFFICE.

JOHN EDWARD THORNTON, OF WEST HAMPSTEAD, LONDON, ENGLAND.

CINEMATOGRAPH AND PHOTOGRAPHIC COLOR FILM MATERIAL.

Application filed October 3, 1925, Serial No. 60,349, and in Great Britain November 3, 1924.

This invention relates to the manufacture of multi-color film-material for the production of cinematograph or other form of photographic films of the type described in my U. S. Patent No. 1,635,516 dated July 12, 1927, and in my application for U. S. Patent, Serial No. 711,255 filed May 5, 1924, and in British Patents No. 214,934 dated December 27, 1922 and No. 233,985 dated November 10, 1924, in which the film-material is formed with differently-colored stripes side-by-side.

Hitherto such films have been constructed by applying differently-colored colloid emulsions in side-by-side stripes to a base or support of celluloid or the like and it has been found difficult to so adjust the coating machinery as to ensure exactly the same thickness of emulsion and therefore equal density of the different colors when using a separate 20 coating roll for each stripe.

By the present invention this difficulty is overcome, and even results are produced, with less labour and attention.

In the accompanying drawings:

25 Fig. 1 is a sectional view of a transparent support having a layer of adhesive substratum applied thereto and illustrating the first step in the production of the film.

30 Figs. 2, 3 and 4 are views similar to Fig. 1 illustrating the second, third and fourth steps in the production of the film.

Fig. 5 is a plan view of a portion of the finished film; and

35 Fig. 6 is a sectional view of an apparatus suitable for use in applying the stripes of color to the colloid layer on the transparent support.

40 The film-material is preferably formed as a very wide web and afterwards slit into multi-color strips of the desired width.

The base or support consists of celluloid, cellulose-acetate or other suitable transparent waterproof material, or it may be gelatine, paper or other material.

45 The base is coated all over by means of standard coating machinery with a layer of adhesive substratum of the usual known types and upon the substratum a layer of colloid, such as gelatine, albumen or fish glue having 50 one even thickness throughout. The colloid may have its sensitizer incorporated therewith before coating or it may be applied afterwards. For example, where silver-bromide is used it is formed into a sensitive 55 emulsion by incorporation with gelatine as the colloid in the usual way. But if the

sensitizer consists of a bichromate salt, iron salt, or other substance not usually made up into emulsion form, it is preferred to coat the support all over with the colloid such as 60 gelatine, albumen, or fish glue, dry the layer, and afterwards apply the sensitizer thereto by any of the known methods.

The dyes or liquid colors are made up into 65 solutions of the requisite strength and are then applied to the dry colloid layer in parallel stripes of the requisite widths and arrangement of colors; each color being applied by a separate coating roll and trough of the usual description; or by a coating device comprising a flow-weir; or by a spray; or other means which will apply a coating of controllable width.

70 The exact intensity or depth of color is ensured by making up each color-solution 75 to a definite strength, and then applying each colored-solution to the web for a sufficient time to ensure complete saturation of the colloid layer through its total thickness over the width of each stripe. When the full 80 quantity of color has been absorbed by the colloid the latter is then dried, after which the web is slit up into narrow strips, each containing two, three, four or other number of differently colored stripes side-by-side. 85

Any required variations in density of coloring may be made by suitable adjustments in strength of the coloring solutions.

90 Any mordant suitable to the particular dye or color colloid is used for fixing the colors, which mordant may, in the case of some dyes, be incorporated in the coloring solutions, but in most cases it will be preferred to fix the colors by applying a mordant to the entire width of web after the 95 stripes of colors have been first applied and dried.

99 Where it is desired to more accurately limit the flow of the dyes and absorption by the colloid in the lateral direction in order 100 to ensure sharper edges or limit to each width of color, a hardening solution or a mordanting solution may first be applied to the web in the form of border stripes in the margins between the colored stripes, such 105 lines of solution being absorbed by the colloid and dried before the colors of the stripes are applied, the hardened or mordanted borders limiting any flow or absorption of colors in those directions.

110 What I claim as my invention and desire to protect by Letters Patent is:—

1. A multi-colored positive film-material comprising a web of cellulosic base material, an adhesive substratum over the entire width of said web, an even layer of colloid over the entire width of the substratum, a plurality of narrow border stripes at intervals on said layer of colloid, and a plurality of colored stripes absorbed in the colloid layer between said border stripes. 5
- 10 2. A multi-colored positive film material, comprising a web of cellulosic base material, an adhesive substratum over the entire width of said web, an even layer of colloid over the entire width of said substratum, a plurality of narrow border stripes at intervals on said layer of colloid, a plurality of colored stripes 15 absorbed to saturation point in the colloid layer between said border stripes, and a layer of mordant over the entire width of said web.
- 20 3. A multi-colored positive film-material, comprising a web of cellulosic base material, an adhesive substratum over the entire width of said web, an even layer of colloid over the entire width of said substratum, a plurality of narrow border stripes at intervals on said 25 layer of colloid, a plurality of colored stripes absorbed to saturation point in the colloid layer between said border stripes, and a layer of mordant over the entire width of said web.

In testimony whereof I have hereunto set my hand.

JOHN EDWARD THORNTON.
